(57) **CLAIM**

The ornamental design for a connector for a nasal cannula
assembly as shown and described.

DESCRIPTION

FIG. 1 is a top, front and right side perspective view of a
connector for a nasal cannula assembly embodying our new
design.

FIG. 2 is a top, rear and right side perspective view thereof.
FIG. 3 is a top view thereof.

FIG. 4 is a bottom view thereof.

FIG. 5 is a right side view thereof.

FIG. 6 is a left side view thereof.

FIG. 7 is a front view thereof; and,

FIG. 8 is a rear view thereof.

1 Claim, 4 Drawing Sheets
